ABRADER ATTACHMENT FOR WRITING INSTRUMENTS

William C. F. Ehrmann, Fort Wayne, Ind.

Application April 13, 1936, Serial No. 73,994

5 Claims. (Cl. 120—39)

This invention relates to improvements in abrader attachments for fountain pens, pencils and similar instruments, and an object thereof is to provide an attachment adapted to be removably mounted upon a writing instrument or other suitable support and having an adjustable tongue one end portion of which is finely toothed on one of its surfaces to provide an abrading face, and the opposite end of the tongue being shaped suitably to form a finger clip to hold the instrument and the device in a pocket by engagement of the clip over the front of the pocket as writing instruments having a clip are usually held.

Another object is to construct the attachment so there is provided a shelter in which the abrading face is concealed when the tongue is moved into one of its positions of adjustment.

A further object is to provide an instrument that is conveniently carried and readily brought into use for effecting erasures, polishing of various objects or for manicure purpose.

Other objects and advantages of the invention will appear in the following description.

An illustrative embodiment of the invention is shown in the accompanying drawing, in which:—

Fig. 1 is a front elevation of a fountain pen provided with an attachment in which the invention is embodied, the abrader being in sheathed position;

Fig. 2 is a similar elevation projected from Fig. 1 in a plane at right angles thereto;

Fig. 3 is an elevation similar to that of Fig. 1 showing the abrader when in extended position for use;

Fig. 4 is a side elevation projected from Fig. 3;

Fig. 5 is a fragmentary enlarged front elevation partly cut away showing the abrader in extended position; and

Fig. 6 is a side elevation projected from Fig. 5 showing the abrader in sheathed position, partially in section.

The illustrations show the invention as applied to a fountain pen of the usual construction having a barrel 1 provided with a removable cover cap 2 which when in place upon the barrel shelters the nib 3 of the pen. Upon the lateral face of the cap is secured a sheath 4 preferably consisting of a metallic channel 5 that is secured directly to the cap by any suitable means such as prongs or rivets 6, and another channel that is fitted telescopically upon the other channel and forms a cover 7 therefor. The sheath thus formed is open at its top and bottom, and the opening 55 through the bottom is restricted to a limited

extent by an inwardly turned ledge 8 hereinafter referred to.

Extending lengthwise through the sheath is disposed a longitudinally movable tongue 9 formed of spring metal that is slightly arcuate from one of its ends to the other. The middle portion of the tongue tends to bow outwardly, and one of its sides has made therein notches 10 and 11 (Fig. 5) adapted to receive a spring finger 12 that is formed by slitting the corresponding side wall of the channel 5, thus to hold the abrader in extended or sheathed positions accordingly as the tongue is adjusted.

The outer face of the lower portion of the tongue is smooth, and bears against the inwardly turned ledge 8 so that the tongue is constantly pressed toward the inner channel 5 and the cap 2. Thus, the outer face of the upper portion of the tongue which is finely toothed to provide an abrading face 13 is held at all times from contact with the inner wall of the cover 7 which obviates injury thereto during adjustment of the tongue.

The lower end of the tongue preferably is coiled to form an enlargement 14 and constitutes a clip 15 when the abrader is sheathed for securing the pen and the attachment to the front of a garment pocket.

In use, the pen or other support to which the attachment is secured serves as a handle for manipulating the device, and the abrading face on the tongue is readily moved into extended or operating position by sliding the tongue upwardly in the sheath. Erasures from surfaces or polishing thereof is effected by stroking the surface where erasure or polishing is required with the abrading surface of the tongue and using more or less pressure manually applied to the back of the tongue.

I claim:

1. An attachment for a writing instrument constituted of a channel having means for attachment to said instrument, a cover member disposed telescopically on said channel closing the front thereof and having at one end an inwardly turned ledge, and a spring tongue disposed between the channel and cover adapted to have longitudinal adjusting movement therebetween, said tongue being normally arcuate from one end to the other, one end portion of said tongue being finely toothed to provide an abrading face, and the opposite end being formed to provide a clip for securing said attachment and instrument in a pocket.

2. An attachment for a writing instrument con-

stituted of a sheath having open ends and having means for attachment to said instrument, said sheath having at one end an inturned ledge, and a normally arcuate spring tongue extending 5 through said sheath and longitudinally movable therein, one end portion of said tongue being toothed to provide an abrading face, the middle and opposite end portions of said tongue being smooth, having bearing relation with said ledge, 10 and constituting a clip for securing said attachment and instrument in a garment pocket.

3. An attachment for a writing instrument and the like, a sheath having means for attachment to said instrument, a normally arcuate spring 15 tongue extending through and longitudinally movable in said sheath, and means to frictionally hold said tongue in different positions of adjustment in said sheath, one end portion of said sheath being toothed to provide an abrading face, and 20 the opposite end portion of said tongue con-

stituting a clip for securing said attachment and instrument in a garment pocket.

4. An attachment for a writing instrument and the like, a sheath having means for attachment to said instrument, and a normally arcuate spring 5 tongue extending through and longitudinally movable in said sheath, one end portion of said tongue being toothed to provide an abrading face adapted to be projected into position for use beyond the corresponding end of the sheath or 10 drawn into the sheath to be sheltered thereby accordingly as said tongue is adjusted.

5. In an instrument of the class described, a sheath and support therefor, a normally arcuate spring tongue extending through and longitudinally movable in said sheath, one end portion of said tongue having an abrading face, and means 15 on said sheath for frictionally holding said tongue in positions of adjustment in said sheath.
